UNITED STATES PATENT OFFICE.

JOHN W. DICKSON AND STEPHEN J. ELY, OF CASTLEROCK, WASHINGTON.

DOOR-FASTENER.

No. 801,369.

Specification of Letters Patent.

Patented Oct. 10, 1905.

Application filed March 13, 1905. Serial No. 249,891.

To all whom it may concern:

Be it known that we, JOHN W. DICKSON and STEPHEN J. ELY, citizens of the United States, residing at Castlerock, in the county of Cow-
5 litz and State of Washington, have invented certain new and useful Improvements in Door-Fasteners; and we do declare the following to be a full, clear, and exact description of the invention, such as will enable others skilled
10 in the art to which it appertains to make and use the same.

This invention relates to improvements in door-fasteners.

The object of the invention is to provide a
15 device of this character whereby a door may be securely fastened or locked on the inside.

A further object is to provide a fastening device for doors which may be quickly and easily applied to the same and which when
20 not in use may be easily carried about by the person possessing the same, said fastening being simple, strong, durable, and light in construction, efficient in use, and well adapted to the purpose for which it is designed.

25 With these and other objects in view the invention consists of certain novel features of construction, combination, and arrangement of parts, as will be hereinafter described and claimed.

30 In the accompanying drawings, Figure 1 is a horizontal sectional view through a portion of a door and the door-jamb, showing the application of the invention. Fig. 2 is a detail perspective view of the fastening re-
35 moved from the door. Fig. 3 is a side elevation, partly in section. Fig. 4 is a transverse sectional view taken through the adjustable stop and the locking-pin arranged therein, and Fig. 5 is a detail view of the locking-pin
40 removed from the stop.

Referring more particularly to the drawings, 1 denotes the fastener, which consists of a bar or plate 2, one end of which is bent at right angles and provided with teeth or
45 prongs 3. On one edge of the plate or bar 2 is formed a series of ratchet-teeth 4. In the end of the plate opposite to that having the teeth or prongs 3 may be formed an aperture or eye 5, by which the fastener may be hung
50 upon a nail or hook.

Slidably mounted upon the plate or bar 2 is a stop 6, said stop being preferably in the form of a rectangular block one end of which is provided with an offset or enlargement 7.

55 In the stop 6 is formed a longitudinally-dis-

posed slot or aperture 8, through which the plate or bar 2 is adapted to pass. In the stop 6 is also formed a transversely-disposed aperture 9, which intersects the slot 8. In the aperture 9 is slidably mounted a locking-pin 60 or bolt 10, in which is formed a vertically-dis-
posed slot 12, the upper wall of which is inclined to form a tooth 13.

The plate or bar 2 is adapted to pass through the slot 12 of the pin or bolt, the teeth 4 on 65 said plate being engaged by the tooth 13, formed in the slot 12 of said bolt. On one end of the pin or bolt 10 is formed a head 14, between which and the adjacent side of the stop 6 is arranged a coil - spring 15. One 70 end of said spring 15 is connected to the head of the bolt, while the opposite end of the same is connected to the side of the stop 6, the tendency of the spring being to normally hold the pin or bolt 10 in a retracted position to en- 75 gage the tooth 13 thereon with the ratchet-teeth 4 of the plate or bar 2, thus permitting the stop 6 to be adjustably secured to said plate or bar.

In applying the device to a door the plate 80 or bar 2 is arranged between the edge of the door and the adjacent side of the door-jamb, the teeth or prongs 3 on the end of the plate being forced into the jamb, as shown in Fig. 1 of the drawings. After the plate 2 has been 85 so arranged and the door closed the stop 6 is slipped onto the inner end of the plate and forced upwardly into engagement with the door. In forcing the stop 6 against the side of the door the teeth 13 on the locking-bolt 90 will slide loosely over the ratchet-teeth 4 of the bar until said stop has been brought to the proper position. The engagement of the tooth 13 with the ratchet-teeth 4 will prevent the stop from being moved in the opposite di- 95 rection until said tooth has been disengaged from the ratchet-teeth by the shifting of the locking-bolt, as will be clearly understood, thus holding the door in closed position.

From the foregoing description, taken in 100 connection with the accompanying drawings, the construction and operation of the invention will be readily understood without requiring a more extended explanation.

Various changes in the form, proportion, 105 and the minor details of construction may be resorted to without departing from the principle or sacrificing any of the advantages of this invention.

Having thus described our invention, what 110

we claim as new, and desire to secure by Letters Patent, is—

The herein-described door-fastener, consisting of a plate or bar having formed on one 5 end right-angularly-projecting teeth or prongs and on one edge a series of ratchet-teeth, a slotted block adjustably mounted on said plate or bar to form a stop, a pin or bar slidably mounted in said block, and provided with a 10 slot through which the plate or bar passes, a tooth or pawl formed in the slot of said pin to engage the ratchet-teeth on said plate or bar

and a spring to normally hold said pin in position to engage said pawl with the ratchet-teeth of said plate or bar, substantially as described. 15

In testimony whereof we have hereunto set our hands in presence of two subscribing witnesses.

JOHN W. DICKSON.
STEPHEN J. ELY.
